UNITED STATES PATENT OFFICE.

CHARLES W. GREEN, OF MILLBURN, NEW JERSEY, ASSIGNOR TO WESTERN ELECTRIC COMPANY, INCORPORATED, OF NEW YORK, N. Y., A CORPORATION OF NEW YORK.

AMPLIFYING SYSTEM.

Application filed July 19, 1924. Serial No. 726,929.

This invention relates to wave amplifying systems, particularly to systems employing space discharge amplifiers, and more particularly to systems adapted to amplify waves within a wide range of frequencies.

One object of the invention is to provide an amplifier which offers to waves of widely differing frequencies impressed upon its input terminals an impedance that is substantially constant. A second object is to increase the input impedance of amplifiers to a high value for a wide range of impressed frequencies. A related object is to secure an increased degree of amplification as the result of the improvement of the input impedance characteristic of the amplifying device.

A feature of the invention is a feed back path between the output and the input circuits of an amplifier which includes an impedance element or a network of impedances proportioned in a particular manner so that substantially all or a predetermined portion of the input energy is furnished from the output of the amplifier.

It is well known that the impedance between the input terminals of a space discharge amplifier has the characteristic variation of a capacitive reactance and that even at low frequencies its magnitude is not so great that the shunting effect may be ignored. The common practice of stepping up the voltage of the impressed waves before it is applied to the amplifier terminals meets with a limitation due to this property of the discharge tubes, the greatest voltage ratio being completely determined in accordance with well known principles, by the relative magnitudes of the amplifier input impedance and the impedance of the wave source. The decrease of the input impedance with increasing frequency results in a decreased value of the maximum voltage ratio that can be obtained; consequently, a transformer adapted to step up the voltage most efficiently at one frequency cannot maintain the same voltage transformation at higher frequencies, and, in fact, is unable to produce even the lower ratio determined by the impedances at the higher frequencies. The diminution of the voltage as compared with the maximum obtainable is due to the so-

called reflection loss resulting from the mismatching of the impedances by the transformer. As the frequency increases it may become so great as to completely counterbalance the gain in the amplifier.

In communication systems it is frequently required to transmit waves having a very wide frequency range. For example, the faithful reproduction of music transmitted by telephone currents may require the transmission with uniform efficiency of all frequencies between 100 cycles per second and 5000 cycles per second, a ratio of 1 to 50; or again, the operation of a multiplex carrier wave system may require the use of amplifiers amplifying uniformly currents of all frequencies between 3,000 C. P. S. and 30,000 C. P. S. To meet these requirements it has generally been necessary to use transformers having a low transformation ratio suited to the efficient transmission of frequencies near to the higher limit, the amplification of the lower frequencies being sacrificed in consequence.

Another disadvantage arising from the variation of the input impedance of an amplifier is realized when selective circuits such as filters or transmission equalizers are inserted in the input circuit of the amplifier. Circuits of this type should be terminated in constant non-reactive resistances in order that their selective properties may be utilized with the greatest precision. If no input transformer is used the effect of the discharge tube input impedance may be negligibly small, but if a step-up transformer is used, the effect becomes greater and is increasingly large as the step-up ratio is increased. This is due to the well known property of transformers by which the secondary load impedance appears in the primary side transformed according to the square of the voltage transformation ratio.

According to this invention these difficulties are overcome by furnishing the current required by the amplifier input impedance from the amplified output current. This is accomplished by providing a feed-back circuit in which an E. M. F. is generated substantially alike in phase to that impressed on the discharge tube input terminals and in which the magnitude of the current is con-

trolled by an impedance of predetermined value. When the impedance of the feed back circuit is adjusted to the proper value, the input impedance becomes substantially infinite for a wide range of frequencies in so far as it affects the impressed waves and its shunting effect thereon is reduced to a negligible amount.

The invention will be more fully understood from the detailed description and analysis which follows taken in connection with the accompanying drawings of which

Fig. 1 shows an amplification system embodying the invention;

Fig. 2 represents a modified form of the feed-back circuit;

Fig. 3 illustrates a modified form of the invention in which an additional degree of freedom is permitted in the proportioning of the feed back circuit.

Figs. 4 and 5 show additional methods of furnishing current to the input circuits;

Figs. 6 and 7 disclose the invention applied to amplifiers of the push-pull type; and

Fig. 8 is a theoretical diagram for the purpose of illustrating the principles involved.

To simplify the explanation of the other figures the circuit of Fig. 8 will be first discussed. In this figure only the important impedances and E. M. F. sources of a system involving the invention are shown, and these in conventional form.

Waves from a source G having an E. M. F. E_0 are transmitted through a line of impedance Z_1 to an impedance Z_4 which is of the proper magnitude and type for terminating the circuit. In parallel with Z_4 is an impedance Z_3 , the effect of which upon the waves from source G it is desired to neutralize. To effect the neutralization a circuit containing a source F of E. M. F. E_2 and an impedance Z_2 is connected to the terminals of impedance Z_3 .

The E. M. F. E_2 of source F is assumed to have the same frequency as that of source G and to be of like phase so that the currents from the two sources tend to oppose each other in the section of the line between points C and D. The condition that the impedance Z_3 take no current from the source G is the same as the condition that the current I in the branch C. D. be zero irrespective of the values of the two E. M. F.'s. It may be shown that this condition is defined by the following equations

$$E_1 = E_0 \frac{Z_1}{Z_1 + Z_4} = E_2 \frac{Z_3}{Z_3 + Z_2 + Z_5}$$

or

$$Z_2 + Z_5 = Z_3 \left\{ \frac{E_2}{E_1} - 1 \right\} \quad (1)$$

in which Z_5 is the internal impedance of the source F and E_1 is the fractional part of E_0 that is applied to the terminals of Z_4 .

The two E. M. F.'s being of the same frequency and of like phase the multiplying factor of Z_3 on the right hand side of Equation (2) is a simple numeric. If then by suitable circuit arrangements the E. M. F. E_2 is caused to bear a constant ratio to E_1 the neutralization may be accomplished by constructing the impedance Z_2 so that its joint impedance with Z_5 is a simple multiple of the impedance Z_3 at all frequencies.

75

Since the impedance Z_5 is in general fixed by other conditions it may in certain instances be impossible to construct the impedance Z_2 to fulfill this condition rigorously. For example Z_3 may be of the nature of a pure capacity and Z_5 a resistance in which case there is no known structure for Z_2 that will provide at all frequencies a simple numeric ratio of the impedance $Z_2 + Z_5$ to the impedance Z_3 . If, however, Z_3 is large and if E_2 is at least twice as great as E_1 it will generally be found that the impedance Z_5 is negligibly small.

80

It is to be noted that the impedance Z_3 need not be a simple impedance element but may consist of a network of elements of any type, the impedance Z_2 being constructed in the form of a similar network each element of which is related in magnitude to the corresponding element of Z_3 in a constant ratio.

95

In a space discharge amplifying system involving the invention the E. M. F. impressed on the feed back circuit corresponds to E_2 and being derived from the energy of the amplifier output, is readily maintained in the desired relationship as regards phase and magnitude, to the input E. M. F. There being substantially no transfer of energy through the amplifier this E. M. F. may, except for its control as to phase and magnitude, be considered as originating in a separate source, the internal impedance of which is principally that of the normal load and the space path of the amplifier jointly in parallel.

100

In the system of Fig. 1 waves from the source G are transmitted through a line or other impedance network 1 to the voltage regulating potentiometer 2 and to the input transformer 3 in which they are stepped up in voltage before being impressed upon the input terminals B and C of amplifier 4. Amplifier 4 is of the customary three-electrode space discharge type having included in an evacuated space a cathode 5, an anode 7, and a control electrode 6. In the output circuit of the amplifier the waves are transformed and reversed in phase in transformer 8 from the secondary winding 9 of which they are delivered to the load impedance 10. From terminal D of the secondary winding 9 the reversed E. M. F., which by reversal is brought into like phase with the impressed E. M. F., is fed back to the control electrode terminal B through a

125

130

condenser 11 of small capacity to furnish the current required by the input impedance of the amplifier.

The factors that enter into the input impedance of a space discharge amplifier are principally the inter-electrode capacities and the effective amplification factor. In addition to these may be included the external capacities between the input terminals, for example, that of the wiring and the shunt capacity of the input transformer windings.

The input capacities are shown dotted at 12 and 13, 12 representing the capacity between the control electrode and the anode, 15 and 13 representing the total direct capacity between the input terminals. It may be shown that the effective input capacity has the value C_e given by the following equation:

$$C_e = C_{13} + C_{12}(1 + \mu_e) \quad (2)$$

in which C_{12} and C_{13} are respectively the values of the capacities 12 and 13 and μ_e is the effective amplification as measured by 25 the ratio of the wave voltage at the amplifier output terminals to the input voltage at terminals B and C.

It is evident from Equation (1) that the condenser 11 is the correct type of impedance to neutralize the effect of the tube input capacity. A knowledge of the various factors indicated above permits the proper value to be readily determined. As an example, the values for a system similar to 30 that of Fig. 1 using a space discharge amplifier of a common type, will be given. For this amplifier, the part of capacity 13 within the discharge tube itself has a value of 12.5 micro-microfarads and the part due to the 35 external wiring is generally about 50 micro-microfarads in systems designed to operate at frequencies up to 50,000 cycles per second. The capacity 12 has a value of 6 micro-microfarads. The amplification constant is 40 6 and the space discharge path has an effective resistance of 5,000 ohms. It will be assumed that the transformer 9 has a one-to-one ratio and that impedance 10 has a resistance equal to that of the space discharge 45 path. The internal and external parts of the output circuit impedance being equal the effective amplification is equal to half the amplification constant. Substitution of these values in Equation (2) gives a value 50 for C_e of 86.5 micro-microfarads. At a frequency of 50,000 cycles per second the impedance corresponding to this capacity is 55 27,000 ohms and at lower frequencies is greater in the inverse ratio of the frequency. 60 The portion of the feed-back circuit between junction point D and the cathode comprises in effect two parallel paths namely the space discharge path, in which the E. M. F. is produced, and the load impedance 10, the transformer 9 in addition to having unity ratio

is assumed to have very high impedance windings and substantially perfect coupling so that its own impedances may be ignored. In accordance with a well known circuit theorem this part of the circuit may, with respect to its relationship with the remaining part 11, be replaced by a single branch having an impedance equal to that of the two actual branches in parallel and containing an E. M. F. equal to the actual E. M. F. at the junction terminals of the two branches. Applying this theorem to the example chosen the impedance corresponding to Z_5 of Equation (1) is half of the space path resistance or 2500 ohms, and the effective value of the E. M. F. in the feed back circuit is three times the input E. M. F. The total impedance of the feed back circuit should therefore be twice the amplifier input impedance which even at the highest frequency considered is very large in comparison with the internal resistance of the feed back source. Ignoring the effect of Z_5 it is seen that the capacity 11 should have a value equal to one half that of C_e or about 43 micro-microfarads.

As already pointed out it is possible to furnish from the amplifier output the current to other impedances shunting the input circuit. In Fig. 2 which represents an alternative form of that part of Fig. 1 above the section line AA' an inductance 14 is shown in parallel with the capacity, the purpose being to furnish the magnetizing current of the input transformer. The input transformer is in effect an inductance in parallel with the amplifier capacity and the component of the input current taken by it is therefore furnished through the inductance 14 in parallel with the capacity that compensates the amplifier capacity.

The system of Fig. 3 is similar to that of Fig. 1, except that the feed back or neutralizing impedance 16, the form of which is not restricted, is connected to a third winding 15 of transformer 8. The reason for this is that the transformer ratio required for the transmission of maximum energy to the load 10 is not in general the same as that which will result in largest ratio of the feed back impedance 16 to the internal impedance of the feed back source. The following analysis indicates the best value of the latter transformation ratio. It is assumed that the impedance 16 is so great as to constitute an inappreciable load upon the amplifier. Let the resistance of the space path be denoted by R and the transformed impedance of 10 as viewed from the amplifier output terminals be denoted by $M R$. If the impedance of 10 contains a reactive component, M will be an imaginary or a complex quantity. Further, let the amplification constant of the discharge tube be denoted by μ and the voltage ratio of transformer 8 from 130

the primary winding to the feed back winding 15 be denoted by N . In accordance with the circuit theorem already enunciated the effective impedance of the E. M. F. source 6 in the feed back circuit is equal to

$$R \times N^2 \times \frac{M}{1+M} \quad (3)$$

and the E. M. F. therein corresponding to 10 an E. M. F. E_1 impressed upon the amplifier input terminals B and C is equal to

$$E_1 \times \mu \times \frac{M}{1+M} \quad (4)$$

15 The first of these quantities may be substituted in Equation (1) for the impedance Z_5 and the second for the E. M. F. E_2 and the following equation for the ratio of Z_2 to Z_5 derived therefrom.

$$\frac{Z_2}{Z_5} = \frac{Z_3}{R} \times \left\{ \frac{\mu}{N} - \frac{1}{N^2} \frac{1+M}{M} \right\} - 1 \quad (5)$$

The transformation ratio N corresponding to the maximum value of the ratio is given 25 by the equation

$$N = \frac{2}{\mu} \frac{1+M}{M} \quad (6)$$

30 This value evidently may differ considerably from the required for the maximum energy transmission to the load impedance. It follows from Equation 6 that the E. M. F. in the feed back circuit should be twice the E. M. F. impressed upon the amplifier input terminals and the impedance included in the feed back path should be equal to the impedance to be neutralized.

Instead of predetermining the proper 40 magnitude of the feed back impedance by computation from the coefficients of the other elements of the circuit the value may be determined and adjusted by trial. This method is particularly advantageous for determining the small capacity required to neutralize the input capacity of the discharge tube. To permit making the adjustment the condenser 11 must be variable and a sensitive current measuring device should be inserted in series with the secondary winding 45 of transformer 3. A wave, preferably of a relatively high frequency in the transmission range of the amplifier, is impressed upon the input circuit from source 1, thereby setting up a counter E. M. F. in the feed back circuit. The condenser 11 is then adjusted until the input current as measured by the current indicator has a minimum value, which should be substantially zero. If it is desired to include in the neutralized impedance 50 the capacity of the input transformer windings the adjustment should be repeated with the current measuring device connected directly in series with the transformer primary winding. In addition the impressed wave should be of the highest frequency it

is desired to transmit. To reduce the current in this branch of the circuit to a minimum value it will in general be necessary to increase the capacity of condenser 11. The condition that is reached when the adjustment has been reached is that the inductance of the transformer secondary winding is in resonance with a small residual capacity. Since in practice the transformer resonance 70 usually occurs at a frequency quite low in the transmission range, the condition reached as the result of the adjustment leaves only an extremely small fraction of the capacity effective in the circuit.

In the system of Fig. 4 the reversal of the feed back E. M. F. is accomplished by means of an auxiliary amplifier instead of by a transformer. Part of the output wave energy from the amplifier 4 is transmitted through condenser 17 and impressed upon the input terminals of the space discharge amplifier 18, the capacity of condenser 17 being large enough to make its impedance negligibly small. The output of amplifier 18 is delivered to a variable potentiometer 19, the adjustable contact of which is connected to the neutralizing capacity 11 and thence to the input terminal B of the amplifier 4. A high resistance 20 connected between the input terminals of the auxiliary amplifier serves as a leakage path for charges that might otherwise accumulate upon the control electrode. The adjustment of the feed back circuit in this case may be accomplished by varying the setting of the potentiometer whereby the feed-back voltage is adjusted to the proper value for neutralization.

The systems of Figs. 1, 3 and 4 illustrate the application of the invention to a single amplifier supplying energy to a load impedance. In these systems it is obvious from the foregoing analysis that the phase of the feed-back voltage is affected to some extent by the phase angle of the load impedance. To secure the most complete neutralization it is therefore desirable that the load impedance be nearly non-reactive, or alternatively that it be large in comparison with the space path impedance of the amplifier.

In the system of Fig. 5 the input impedances of amplifiers connected in tandem are neutralized, the phase reversal of the feed-back E. M. F. being secured by connecting the feed back circuit between the anode of one amplifier and the control electrode of the preceding amplifier. The coupling between the successive amplifiers comprises high impedance space current supply coils 23, stopping condensers 24 and leakage path resistances 25. The feed back circuit from the anode of the second amplifier 21 to the input terminal of the first amplifier 4 includes the neutralizing impedance 16 and a large condenser 17 to isolate the energiz- 125

ing potential of the amplifier 21. The feed back circuit between amplifiers 22 and 21 is of similar form. The type of coupling used in this system between the successive 5 stages is such that the external impedance of each output circuit is very large in comparison with the internal space path resistance and in consequence has but a small effect upon the phase of the feed back E. 10 M. F.

The system of Fig. 6 comprises two space discharge tubes 26 and 27, the input and the output circuits of which are connected together in the well-known "push-pull" arrangement. The E. M. F. waves from the source 1 being impressed upon the input terminals through the three winding transformer 28, the two secondary windings of which are accurately balanced to produce 20 equal voltages. The output voltages of the two amplifiers being in opposition, each may be utilized as a source of E. M. F. for neutralizing the input impedance of the other. Two feed-back paths are provided, each extending from the anode of one tube to the control electrode of the other and including the neutralizing impedance 16 and the isolating condenser 17.

The system of Fig. 7 is similar to that of 30 Fig. 6, except that the feed-back E. M. F. is transformed in auto-transformers 29 and 30 in the proper ratio to reduce to a minimum the effect of the discharge tube and load impedances. The operation of the systems of Figs. 6 and 7 is similar with that of 35 the systems shown in the preceding figures and the limitations that were discussed in connection therewith apply also to these systems.

40 What is claimed is:

1. A wave amplifier comprising at least one space discharge amplifier tube, an input circuit for said amplifier including a wave source, an output circuit for the waves of 45 amplified energy, and means for applying part of the energy of said amplified waves to neutralize the flow of current from said source to the input terminals of said amplifier.

50 2. A wave amplifier for waves of a wide range of frequencies comprising at least one space discharge amplifier tube, an input circuit for said amplifier coupled to a source of waves of a wide range of frequencies by a 55 step-up transformer, an output circuit for the waves of amplified energy, and means for applying part of the energy of the amplified waves to neutralize the flow of current from said transformer to the input terminals of said amplifier.

60 3. In an amplifying system, including a space discharge amplifier, input terminals adapted to receive impressed waves, output terminals having connected thereto a load 65 circuit, and a feed back circuit connected to

said input terminals and by means of a transformer to said output terminals, said feed back circuit including an impedance equal to that of said amplifying system between its input terminals and said transformer being adapted to produce in the feed back circuit an electromotive force equal to twice that of the electromotive force produced in said impressed waves. 70

4. An amplifying system comprising an 75 amplifying device having a pair of input terminals, a circuit connected to said terminals including a wave source, and a feed back circuit connected between said terminals, said feed back circuit being adapted to impress on said terminals a feed back voltage 80 substantially equal in phase and magnitude to the voltage impressed by said source.

5. An amplifying system comprising an 85 amplifying device having a pair of input terminals and having a finite input impedance defined by impedance means between said terminals, a circuit including a wave source connected to said terminals, and a feed back circuit likewise connected between 90 said terminals, said feed back circuit being adapted to neutralize the current flow from the wave source to the said impedance means.

6. An amplifying system comprising an 95 amplifying device, input terminals therefor and a current path between said terminals including impedance means defining the input impedance of said device, a circuit including a wave source connected to said terminals, and a feed back circuit likewise connected between 100 said terminals, said feed back circuit being adapted to receive from the amplified waves a voltage in excess of that impressed upon the input terminals from the wave source and including impedance means 105 whereby the feed back voltage impressed upon the amplifier input terminals is reduced to substantial equality in phase and magnitude to the voltage impressed from the wave source. 110

7. A system in accordance with claim 6 in which the impedance means in the feed back circuit is of similar type to the impedance means defining the input impedance of the amplifying device. 115

8. In an amplifying system, a space discharge amplifier having a cathode and a control electrode constituting input terminals, and impedance means defining the input impedance of the amplifier between said terminals, an input circuit connected to said cathode and control electrode including a wave source, and a feed back circuit also connected to said terminals, said feed back circuit being adapted to impress upon said 120 control electrode a voltage derived from the amplified waves in like phase to the voltage impressed from the wave source, and including impedance means having impedance proportioned with respect to the amplifier 125 130

input impedance whereby the voltages impressed upon the control electrode are substantially equalized in magnitude.

9. In combination, a space discharge amplifier, an input circuit including a wave source connected between the control electrode and the cathode thereof, and means for neutralizing the capacitative input admittance of said amplifier comprising a feed back circuit connected to the amplifier grid, said feed back circuit being adapted to derive from the amplified waves a voltage in phase with the voltage impressed upon the amplifier control electrode by said source, and including a series capacity, the value of which bears to the amplifier input capacity the same ratio as the voltage impressed by the wave source to the corresponding ex-

cess voltage generated in the feed back circuit.

10. An amplifying system comprising a space discharge amplifier, an input circuit connected between the control electrode and the cathode thereof and including a wave source, a feed back circuit including a condenser connected to the amplifier control electrode and coupled to the amplifier space path through a transformer, the windings of said transformer being so poled and the capacity of said condenser being adjusted to such value that the current to the amplifier control electrode from the wave source is reduced substantially to zero.

In witness whereof, I hereunto subscribe my name this 17th day of July, A. D., 1924.

CHARLES W. GREEN.
